CHAIR

Morton Pearlstine, Bala Cynwyd, Pa., assignor to The Bunting Company, Inc., Philadelphia, Pa., a corporation of Pennsylvania

Filed Oct. 24, 1960, Ser. No. 62,607

Term of patent 14 years

(Cl. D15—1)

The dominant features of my design reside in those portions shown in full lines in the drawing.

I claim:

The ornamental design for a chair, as substantially shown and described.
